GAS CONTROL SYSTEM

Christian S. Andersen, Warren, Pa., assignor to
 Pennsylvania Furnace & Iron Co., Warren, Pa.,
 a corporation of Pennsylvania

Application November 29, 1935, Serial No. 52,009

2 Claims. (Cl. 236—1)

This invention relates to the control of gaseous fuel supplied to gas burners, such as are used for heating domestic hot water heaters, or furnaces, boilers or other space heating equipment.

One object of the invention is to provide a gas control system of the character described which is safeguarded from all standpoints, because all gas supply is cut off to the main, pilot, and safety pilot burners in case of either intentional or accidental extinguishment of the flame, or of an abnormal drop in pressure of the gas supply, in any of which situations a manual operation is required in order to supply gas to the safety pilot, coupled with its ignition, before gas can flow to the other control valves or burners.

Another object of the invention is to provide a gas control system of this character which operates by positive pressure of the gas preponderating over atmospheric pressure, which simplifies the connections, the number of operating parts and their functional relationships to each other.

A further object of the invention is to provide a gas control system which dispenses with all leak ports through the diaphragms, with consequent safety in case the fire goes out.

Still another object of the invention is to provide a gas control system which utilizes a master control valve which controls not only the main valve and burner, but also all pilot burners and valves, as a consequence of which effective operation of the master control valve, either manually or automatically, compels safe and proper operation of all other parts.

A further object of the invention is to provide a simple gas control system which is readily controllable either manually when desired, or automatically by the room temperature, or by any desired boiler or furnace function, such as boiler water level, steam pressure, water temperature or the like.

A further object is to provide a system of this character which provides convenient dual control of a water boiler, a furnace or any heating equipment operated by the burners, with the burners arranged in two or more groups which are successively thrown into and out of operation at various temperatures as conditions vary, all for the purpose of avoiding that undesirable low temperature of the space or device to be heated which occurs when the only regulation of the heating equipment is by simultaneously turning all burners on or off with consequent hunting or unstable conditions.

Further objects of the invention are in part obvious and in part will appear more in detail hereinafter.

In the drawings, Fig. 1 is a diagrammatic view illustrating one embodiment of the invention;

Fig. 2 is a detail sectional elevation of the master control valve and its diaphragm;

Fig. 3 is a detail sectional elevation of the main valve and its diaphragm;

Fig. 4 is a detail section on the line 4—4, Fig. 10 1, illustrating a gas connection;

Fig. 5 is a detail sectional view illustrating a restricted orifice for controlling the gas supply;

Fig. 6 is a detail sectional elevation of a safety pilot burner and valve; and

Fig. 7 is a diagrammatic view, corresponding to Fig. 1, and illustrating a modified arrangement of the parts.

In the drawings, for simplicity of illustration, no device to be heated is illustrated, the drawings showing only several burners together with the gas supply and control features therefor, but without such illustration it is to be understood that the burners may be of any suitable form or character and arranged to heat any kind or character of device, such as the coil or heating unit of a domestic hot water heater, or said burners may be located in the fire chamber of a hot air furnace or in the fire box of a vapor, steam or hot water boiler or the like. For example, the device to be heated may be a hot air furnace of the general type illustrated, described and claimed in a copending application of Horace A. Crary for Furnace construction, filed of even date herewith, Serial No. 51,988, to which reference may be had for a more complete description, if desirable or necessary.

The control system shown in the drawings is designed to control the supply of gas to a plurality, any suitable number, of groups of primary burners, the drawings showing for this purpose a group of two main burners 1, and a group of secondary burners 2, only one of which is shown, although any number of burners may be used in either group and more than two groups may be employed. The gas supply comes from a supply main 3 through an ordinary pressure regulating diaphragm valve 4, beyond which is a pipe 5 leading to a main supply valve 6 and by way of pipe 7 to a master control valve 8. From the main supply valve 6 the gas flows by way of the manifold 9 and standard gas cocks 10 to the primary burners 1 of the first group, while beyond the master control valve 8 the gas flows by way of pipe 11 and cock 12 to the secondary

burners 2 of the second group. For convenience and for the purpose of locating the connections to all burners in the same horizontal plane, the pipe 11 passes directly through the manifold 9 but without communicating with the passage therein, as shown in detail in Fig. 4.

Main supply valve 6 has the stem of its movable valve part connected to a diaphragm 13 in a casing 14, the chamber 15 beneath said diaphragm communicating with a pipe 16. The movable part of the master control valve 8 likewise has its stem connected to a diaphragm 17 in a casing 18, the chamber 19 beneath which communicates with a pipe 20. The chambers above all diaphragms, including diaphragms 13 and 17, as well as the chamber above the diaphragm controlling the pressure regulating valve 4, all communicate freely with or are vented to atmosphere, preferably by way of branches from a pipe 21 communicating with the combustion chamber so as to charge into it and thence to the stack any gas which might accidentally escape as the result of a leaky diaphragm, or for any other reason.

25 The gas flowing through the master control valve 8 is utilized not only to supply the secondary burners 2, in case the latter are used, but also to supply gas for controlling purposes. That is to say, the chamber of valve 8, on the discharge side of said valve, communicates by way of a pipe 22 and stop cock 23 with a suitably restricted orifice 24 through which gas may flow to pipe 20 and also by way of pipe 25 and its branches 25' to one or several, two being shown, of suitably located pilot burners 26, 26'. One of the branch pipes 25' communicates with a combined safety pilot burner and valve marked generally 27 in Fig. 1 and illustrated in detail in Fig. 6. This combined unit includes a casing 28 having a chamber 29 communicating with pipe 25', said chamber containing a spring 30 effective to hold to its seat a valve 31 controlling one or a plurality of burner openings 32, said valve having a stem 33 extending to the outside of the casing and subject to the operating effect of a thermostatic element, such as the bimetallic strip 34, suitably located and arranged so as to be subject to the temperature at or near one of the pilot burners, such as the burner 26' to which it is shown attached. The bimetallic strip is so arranged that when it is heated either by a flame applied to it by hand or by heat communicated to it from the pilot burner, its free end flexes to the left in Fig. 1 and permits the valve 31 to close and cut off the flow of gas from the pipe 25' to the burner ports 32. However, when the parts get cold by extinguishment of pilot flame, then the thermostatic element flexes to the right and opens the flow of gas to the burner ports 32, all subject to control of such flow by other parts, as will appear.

The chamber on the discharge side of the master control valve 8 also communicates with a pipe 35 in which are located one or several control valves subject to such conditions as it is desired to utilize for control of the main burners 1. For example, the pipe 35 may include an electrically operated valve 36 controlled by a thermostat in the room or space to be heated, a valve 37 sensitive to the temperature of water in the boiler, a valve 38 sensitive to level of water in the boiler or a valve 39 sensitive to the pressure of steam in the boiler, or any combination of such valves. Beyond said valves the pipe 35 communicates with an escapement pilot burner 40 and with

the aforesaid pipe 16 leading to the chamber beneath the diaphragm 13 which controls the main supply valve 6.

Pipe 11 may also include an electrically operated valve 41 sensitive to the temperature in the room or space to be heated, as will also more fully appear hereinafter.

Master control valve 8 is also provided with a manually operated by-pass, including a pipe 42 communicating at its opposite ends with the 5 chambers on opposite sides of the movable valve member, said pipe including a self closing valve 43 provided with an operating thumb button 44 which may be depressed to open the valve and hold it open so long as the thumb is held on the 15 button.

Master control valve 8 not only is subject to automatic diaphragm control, as will appear, but is also capable of manual control to either turn it off or to release it so that it may be controlled automatically. For this purpose the casing of its diaphragm supports a rod 45 urged downwardly by a spring 46 to a position in which it holds the movable member or valve 8 to its seat and prevents it from opening, but which rod 26 45 may be elevated by operation of a cam 47 provided with an operating handle 48, in the usual manner. When the handle is thrown to the "off" position valve 8 is closed and all gas flow to all valves and burners is cut off, whereas when 30 the handle is thrown to "on" position, valve 8 may open under certain conditions and permit gas flow, as will appear.

The operation is as follows:

Secondary burners 2, together with the pipe 11 35 and electrically operated valve 41 controlling them, are not essential and may be omitted, as in cases where satisfactory results may be secured by simultaneous operation of all burners, all of which are then included in the group of 40 primary burners 1.

Assuming such an arrangement, let us further assume that all parts are cold and that the space or device to be heated is demanding heat. In that case the thermostatically controlled valve 45 or valves, such as either or both of 36 and 37, are open. It must further be assumed that valve 39 sensitive to steam pressure and valve 38 sensitive to water level, or either of said valves utilized, are open.

To provide heat to supply the demand it is necessary to turn on the gas, ignite it and keep it burning. This is accomplished by moving lever 48 to the "on" position and pressing with the thumb on the button 44 to open the by-pass 42 55 around valve 8. Gas thereupon flows from the pipe 7 through valve 8 to pipe 22. Stop cock 23 is manually opened and is permitted to remain open. Gas then flows through the orifice 24 to each of pipes 20 and 25 and thence to the chamber beneath diaphragm 17 and to the two pilot burners 26, 26' and to the safety pilot 27. All three pilot burners are open and the gas is ignited at these burners. Restricted orifice 24 is of such size as to be incapable of supplying sufficient gas 65 to simultaneously provide full flow through the safety pilot 27 and pilots 26 and 26' and at the same time build up pressure by way of pipe 20 in the chamber 19. As a consequence, the diaphragm 17 at first does not rise. However, ignition of the safety pilot burner 27 heats the bimetallic strip 34, which ultimately moves over and permits valve 31 to move to its seat, thus closing the safety pilot orifice or orifices 32. Thereupon only two pilot burners, to-wit, 26 and 75

26', are open and burning and the additional back pressure through the restricted orifice 24 now available becomes effective through pipe 20 in the diaphragm chamber 19, elevates diaphragm 17 and opens the valve 8. It being assumed that pilot burners 26 and 26' have been ignited, the thermostatic strip 34 will remain flexed, diaphragm 17 will remain elevated, and valve 8 will remain open with free flow of gas therethrough. Push button 44 is now released.

Gas will now flow through the valve 8 and by way of pipe 35 and through the open valves 36, 37, 38 and 39, or such of them as are employed, to the escapement pilot burner 40 and also by way of pipe 16 to the chamber 15 beneath diaphragm 13, elevating the latter and opening and holding open the main valve 6. As a consequence, gas now flows to the burners 1 which are ignited by the pilot burners and continue to burn a full flow of gas.

If at any time the pressure in the lines or passing through valve 4 drops so that the pressure beyond said valve is abnormally low, then said pressure becomes ineffective to support master control valve diaphragm 17, which drops and cuts off the flow through valve 8. Thereupon the gas supplied to each of pipes 22 and 35 is cut off and pressure is evacuated from the main valve diaphragm chamber 15, so that the main valve 6 also closes. Gas remaining in the pipes beyond valves 6 and 8 is evacuated through the main burners 1, through the escapement burner 40, and through the pilot burners. All burners, both main and pilot, including the safety pilot, go out and ultimately the thermostatic strip moves over and opens the safety pilot valve, but no gas flows through said valve. It is then necessary, upon a demand for heat, to restart the entire system in the manner before described.

Likewise, if any one of the valves 36, 37, 38 or 39 closes, such as occurs upon termination of the demand of the room thermostat for heat, upon an abnormal rise in steam pressure, upon an abnormal drop in water level, or upon an abnormal rise in water temperature, or any of them, the flow of gas through pipe 35 is cut off. Thereupon the pressure in chamber 15 beneath the main valve diaphragm is evacuated and main valve 6 closes, remaining closed until the valve or valves which caused its closing operation is again opened to cause a free flow of pressure through pipe 35.

With the arrangement described, it is clear that not only is the main supply valve 6 sensitive to the operation of any one or more of the valves 36, 37, 38 and 39, for automatic control of the gas burners, but also said valve is subject to the operation of the master control valve 3, which in turn is sensitive to manual control and, thermostatically, to automatic control by the safety pilot, and in case all flames are extinguished either intentionally or accidentally, the supply of gas is cut off not only to the main burners but also to all pilot burners, including the safety pilot, and to all valves and diaphragms.

In case dual control is desirable, the group of secondary burners 2, together with the supply pipe 11 and controlling valve 41 for such group, may be employed. Here temperature sensitive valves 36 and 41 are made sensitive, separately, to two thermostats in the room or space to be heated, or to two sets of contacts controlled by the same thermostatic element, or by any other suitable control system so that upon a light demand for heat the secondary burners 2 are first

thrown into operation and may continue in operation for a relatively long period, while the primary burners 1 are thrown into operation only intermittently and upon a greater demand for heat.

The drawings show conventionally a room thermostatic element 50 operating two sets of contacts 51, 52. Contacts 51 are electrically connected with the coil of the secondary control valve 41, while contacts 52 are electrically connected with the coil of the primary control valve 36. The two sets of contacts are so set or adjusted that as the temperature drops first to one value, say 70° F., the contacts 51 are closed, thereby opening valve 41 and permitting the secondary burners 2 to ignite. Under mild weather conditions continued operation of these secondary burners, say one or two burners in a bank of nine in all, may suffice to keep the room nearly at an average temperature of 70°. However, if the temperature falls still farther, say to 68°, the thermostatic element moves over still farther and finally closes contacts 52, so as to energize the coil and operate valve 36, thereby fully opening pipe 35, permitting pressure to flow to the diaphragm 13, which opens main valve 6 and permits the main burners 1 to ignite.

Therefore, with abnormal drop in temperature all burners are finally turned on and continue to operate until the room temperature rises.

Upon rise in room temperature the reverse operations take place, contacts 52 first opening and causing the flow of gas to the primary burners 1 to be cut off, and finally contacts 51 are opened and the secondary burners 2 are cut off.

This system avoids overheating during relatively mild weather, such as during the spring and fall, prevents hunting or unstable temperature conditions and reduces the number of operations of the main thermostat and controls which would be necessary if all burners were simultaneously operated. The ultimate effect is to level out high and low temperature peaks and maintain more nearly uniform the desirable temperature.

Various modifications of the invention will be apparent to those skilled in the art, the invention not being limited to the form shown in the drawings and including all structures within the scope of the claims appended hereto. For example, in the arrangement shown in Fig. 1, the master control valve 3 and main valve 6 are in parallel, as it were, neither of said valves directly supplying gas to the other. Fig. 7 illustrates a modified arrangement in which the same two valves are in series, the master control valve supplying and controlling the supply of gas to the main valve. Most of the parts illustrated in this view are of the same form as those described in connection with Fig. 1, as a result of which they have been given the same reference numbers with the addition of letter *a*, so that detailed description of the various parts will be unnecessary.

Referring to Fig. 7, the arrangement illustrated includes two primary burners 1a and a single secondary burner 2a. The gaseous fuel is supplied by way of a main supply pipe 3a to a standard pressure regulator valve 4a from which it flows by pipe 5a to the master control valve 8a, beyond which is the main valve 6a communicating with a manifold 9a which supplies the primary burners 1a by gas cocks 10a as before. Master control valve 8a and main valve 6a are diaphragm valves of the same form shown in Figs. 2 and 3 respectively, being actuated by diaphragms in the casings 14a and 18a respectively. 43a is the

push button starting valve for the master control valve. It is in a line 42a by-passing valve 8a, beyond which is a pipe 61 communicating by way of the restricted orifice 24a with a pipe 20a communicating with the chamber beneath the diaphragm in casing 18a and by way of a pipe 25a with one or more pilot burners 26a, and with a thermostatic pilot 27a. The chamber beneath the diaphragm in casing 14a communicates by way of a pipe 16a with an escapement pilot burner 40a, and with an electrically operated valve 36a which is thermostatically controlled by room temperature or the like in the same manner as the valve 36, the gas supply connection for the valve 36a being by way of pipe 22a communicating with the pipe 60 which connects valves 8a and 6a. The secondary burner 2a is supplied by way of a pipe 11a which also communicates with the pipe 60 and includes an electrically operated valve 41a which is thermostatically controlled by room temperature in the same manner as the valve 41 before referred to. The upper chambers of the three diaphragm casings all communicate with the same vent pipe 21a, as before.

With this arrangement the operation is quite like that of the form first described.

Assuming all parts cold and with full demand for heat from both room temperature thermostatic circuits, the master control valve handle 48a is thrown to the "on" position, as before, manual push button starting valve 43a is pressed to open it, and gas flows to the pilots 26a and to the thermostatic pilot 27a, all of which are lighted. As soon as the thermostatic element at the thermostatic pilot heats up, the thermostatic pilot valve closes and pressure thereupon builds up beneath the diaphragm in casing 18a to open and hold open the master control valve 8a, as before. The push button can then be released. Gas now flows from valve 8a to valve 6a by way of pipe 60. Assuming that both of valves 36a and 41a are open, due to heat demand, the operation of said two valves is as follows: Gas flows by way of pipes 22a and 16a to the chamber beneath the diaphragm in casing 14a, raises said diaphragm and opens the main valve 6a, so that gas flows to the main burners 1a. Likewise, valve 41a being open, gas flows by way of pipe 11a to the secondary burner 2a. Both the primary and secondary burners are ignited and the furnace continues in operation until the temperature rises, whereupon first valve 36a closes and shuts off the supply to the primary burners, following which valve 41a closes and shuts off the supply to the secondary burners 2a. The operation of the two sets of burners is in sequence and at various temperatures in the manner before described. If the temperature falls, reverse operations take place, the secondary burners 2a being first thrown in and finally the primary burners 1a being thrown in if the demand for heat becomes greater

than can be supplied by the secondary burners alone.

If the thermostatic element at the thermostatic pilot for any reason becomes cold, such as by an emergency failure of gas supply or because the pilots are blown out, then the safety pilot valve 27a opens and robs the diaphragm chamber of the master control valve of the pressure being supplied to it, so that the diaphragm falls and valve 8a closes. This operation cuts off the supply to the chamber of the diaphragm for the main valve, which also closes. As a result, all gas supply is shut off not only to the primary and secondary burners, but also to all pilot burners. Upon resumption of the gas supply or detection of the emergency condition, it is necessary to now start the system by operations beginning with actuation of the push button valve 43a, as before.

In both forms described, full automatic control of all parts offers complete protection against any accidents resulting from escaping gas. If the fire is extinguished by draft or for any other reason the automatic controls completely shut off all gas, regardless of all other conditions, and it is impossible to again turn on the gas to the pilots and burners until the safety pilot has first been manually lighted by the use of the push button and the thermostatic element 34 has been heated sufficiently to maintain open the master control valve 8.

Further advantages of the invention will be apparent to those skilled in the art.

What I claim is:

1. Apparatus of the character described, comprising a primary gas burner, a secondary gas burner, master control valve mechanism which supplies the secondary burner and controls the supply to the primary burner, and two thermostatically operated controlling devices sensitive to the temperature in a space to be heated and located in said space adjacent to each other but remote from both burners, one thereof being effective at one temperature and arranged to control the primary burner, and the other thereof being effective at another temperature and arranged to control the secondary burner.

2. Apparatus of the character described, comprising a primary gas burner, a secondary gas burner, main valve mechanism which supplies the primary burner, master control valve mechanism which supplies the secondary burner and controls the main valve mechanism, and two thermostatically operated controlling devices sensitive to the temperature in a space to be heated and located in said space adjacent to each other but remote from both burners, one thereof being effective at one temperature and arranged to control the main valve mechanism, and the other thereof being effective at another temperature and arranged to control the secondary burner.

CHRISTIAN S. ANDERSEN.
